Delaware

Filed May 2, 1966, Ser. No. 2,100

Term of patent 14 years

(Cl. D71—1)

FIGURE 1 is a perspective view of a first embodiment of a compressor showing my new design;

FIGURE 2 is a top plan view of the compressor shown in FIGURE 1;

FIGURE 3 is a side elevational view of the compressor shown in FIGURE 1;

FIGURE 4 is a bottom plan view of the compressor shown in FIGURE 1;

FIGURE 5 is a perspective view of a second embodiment of the compressor shown in FIG. 1 wherein the only difference resides in the addition of a toroidal float, as shown;

FIGURE 6 is a top plan view of the compressor shown in FIGURE 5;

FIGURE 7 is a side elevational view of the compressor shown in FIGURE 5; and

FIGURE 8 is a bottom plan view of the compressor shown in FIGURE 5.

The dominant features of my design reside in the portions shown in full lines.

I claim:

The ornamental design for a compressor, as shown and described.
